MAIL BOX

Filed Aug. 15, 1927

Inventor

Rebecca Ferabee

By Adam E. Fisher.

Attorney

UNITED STATES PATENT OFFICE.

REBECCA FEREBEE, OF BROOKLYN, NEW YORK.

MAIL BOX.

Application filed August 15, 1927. Serial No. 212,969.

This invention relates to mail boxes for use at the doors of houses, and the object of the invention is to provide a practical and efficient structure of this kind, and one having separate compartments for letters and newspapers.

In the drawing

Figure 1 is a frontal elevation, the outer door being shown open;

10 Figure 2 is a section on the line 2—2 of Figure 1;

Figure 3 is a top plan view;

Figure 4 is a section on the line 4—4 of Figure 1.

15 The invention includes a suitable casing 1, trapezoidal in cross section and with the narrow side facing frontwardly. This casing is provided with a relatively large paper aperture 2 located towards the back, and 20 a relatively small letter aperture 3 in front of the paper aperture. The top 20 of the box slopes downwardly and forwardly as shown. Covers 4 and 5 are hingedly mounted at 6 over these apertures. A large

25 rectangular door opening 7 is formed in the front 21 of the casing 1, and a door 8 is hinged at 9 to close over this opening. The door 8 is provided with a suitable lock 10 and is pierced with peep holes 11 to 30 enable one to ascertain whether there are letters within the box without opening the said door. An inset 12 is formed in the door to receive a name plate (not shown).

A rod 13 is passed through the casing 1 35 from side to side, the same being elevated substantially above the bottom 22 of the casing and arranged in approximate vertical alignment with the hinge 6 of the two covers 4 and 5. A paper cage 14 is provided, the same including a frontal plate 15 which is hingedly mounted at its lower 40 end to the rod 13, a number of upwardly curved paper fingers 16 mounted near the bottom of the plate 15 and extending rearwardly towards the back of the casing 1, and a pair of side arms 17 extending rearwardly from the upper corners of the said plate 15, their extremities being adapted to impinge against the back plate 18 as the 45

50 said paper cage 14 is raised vertically. The arms 17 are of such length that the plates 15

and 18 will stand parallel when the cage is raised. The cage 14 is somewhat smaller than the door opening 7 so that the cage may be readily lowered out through said opening. A coil spring 19 passed over the rod 13 and forming part of the hinged mounting of the plate 15 upon the said rod, in a well known manner, serves to normally hold the cage 14 in its elevated vertical position.

In use the newspapers and bulky articles are deposited through the large opening 2 and fall upon the paper fingers 16, while letters are deposited through the smaller 65 opening 3 and fall upon the bottom of the box. It will be noted that the trapezoidal shape of the box in cross section, presents relatively ample accommodations for newspapers within the paper cage at the back, 70 while smaller space is provided for the letters by the contracted front. At the same time the contracted front preserves the neat appearance of the box.

While I have herein described a certain 75 specific manner and method of constructing and assembling the elements of my invention, it is understood that I may vary from the same in minor details, not departing from the spirit of my invention, so as 80 best to construct a practical device for the purpose intended, as defined in the appended claim.

I claim:

A letter box, comprising a casing trapezoidal in cross section and having a forwardly sloping top, a frontal door opening and relatively large and small mail apertures through its top, covers for the top mail apertures, a door for the frontal door opening, the said door having peep holes cut therethrough, a rod passed transversely through the casing from side to side substantially above the bottom thereof and in vertical alignment with the juncture of the two 90 top mail apertures, a cage hinged to the said rod and adapted to be extended through the said frontal door, and means for normally maintaining the said cage in its vertical position within the casing.

In testimony whereof I affix my signature.
REBECCA FEREBEE.
